UNITED STATES PATENT OFFICE.

EDWARD TAYLOR, OF OWENSBORO, KENTUCKY.

PORTABLE HYDRAULIC STRETCHER.

1,110,838.

Specification of Letters Patent. Patented Sept. 15, 1914.

Application filed March 27, 1914. Serial No. 827,669.

To all whom it may concern:

Be it known that I, EDWARD TAYLOR, a citizen of the United States, residing at Owensboro, in the county of Daviess and 5 State of Kentucky, have invented a new and useful Portable Hydraulic Stretcher; and I do hereby declare the following to be a full, clear, and exact description of the invention, such as will enable others skilled in the art 10 to which it appertains to make and use the same.

In the field of stretchers for hospitals and sanitariums, this invention seeks to provide one of the portable hydraulic kind 15 which combines the greatest utility with the simplest and strongest mechanical structure.

This stretcher is capable of sufficient vertical adjustment to permit it being lowered to the lowest bed or raised to the highest 20 operating table, and as this adjustment is effected by hydraulic means, shocks and jars are rendered impossible. Extensive lateral movement of the stretcher to either side of the truck is provided and this facilitates the 25 removal of patients from their bed to the stretcher and the reverse. Despite its lateral movement, the stretcher may be securely locked in the center of its truck, and all patients are thus insured safe transit with 30 its use. The truck which, with the stretcher, forms the basis of this specification is designed to have the fewest parts consistent with strength and rigidity. These parts are so arranged and proportioned as to eradicate 35 all dust-collecting places and to render the stretcher valuable from a sanitary standpoint.

The device, herewith illustrated, is thought to embody the most efficient design but the inventor reserves the right to alter or change 40 this design to conform to any subsequent design that does not depart from the spirit of what is claimed.

In the drawings:—Figure 1 is a longitudinal elevation of the invention. Fig. 2 is an end elevation, showing in dotted lines the vertical and lateral adjustments. Fig. 3 is a plan of the stretcher. Fig. 4 is a plan of the spring lock which holds the stretcher in 45 the center of its truck. Fig. 5 is a vertical section through the hydraulic lift looking from the operating handle end. Fig. 6 is a part elevation and part section of the major plunger 44. Fig. 7 is a section showing the 50 top of the oil chamber of the hydraulic lift. Figs. 4, 5, 6 and 7 are enlarged views.

In the stretcher truck the frame is made entirely of pipe, the longitudinal pieces 1 connecting to the curved end pieces 2 by means of the pipe elbows 3. These end 50 pieces 2 are curved so as to provide clearance space for the casters 4. Two arcuate pieces 5 are connected in the middle of the frame by the ties 6 and these pieces form a support to which the hydraulic lift 7 is bolted 65 or screwed. The principal weight of the truck is sustained by the cross piece 8 which is upturned at the edge of the frame and bent back at its extremities to form the U-shaped portions 9 wherein the wheels 10 are 70 secured in any suitable manner. This cross piece is preferably made of channel iron, as the flanges of such iron constitute desirable strengthening ribs after the piece has been bent into the shape described. The curved 75 pieces 2 are screwed into the socket members 11 to which the caster forks 12 with their casters 4 are swivelly connected.

At the top of hydraulic base 7 the stretcher and its concomitant parts are secured. Mounted on support 14 is a board 15 at each end of which is a channel piece 16 whose flanges 17 have inserted through them the shafts 18 that carry the rollers 19. These rollers 19 are adapted to turn in the slots 20 85 of the depending pieces 21 attached to the stretcher 22. Stretcher 22 comprises a frame (preferably metal) covered with canvas and having grab handles 23 at each corner and straps 24 at intermediate points on its length. 90 These straps serve to secure patients to the stretcher. At the center is a lock 25 for holding the stretcher in place on its truck. This lock has a case 26 in the bottom of which is a slot 27 wherein a plunger 28 95 slides. In a slot in this plunger the tumblers 29 and 30 rest being pivoted to the case 26 on opposite sides of the plunger and having rounded noses 31 and 32 which protrude through the case. A spring 33 presses 100 against the tumbler 29 which in turn presses against the tumbler 30 causing the plunger 28 to project its required distance out of the case. A cover 34 incloses the case and the whole is secured to the under side of the 105 stretcher 22 in any appropriate manner (not shown). Associated with the lock 25 is a keeper 35 screwed to the board 15. This keeper has a slot 36 to be engaged by the end of the plunger 28 and a groove 37 wherein 110 the rounded noses 31 and 32 slide. The sliding of the noses in the groove 37 presses back

the spring 33 and with it the plunger 28 until the keeper 35 is between the two noses 31 and 32. The plunger 28 then rests on the edge of the keeper 35 until it is in position to engage the slot 36. A string 38 connected to the tumbler 29 passes through the hole 39 in the lock case to the end of the stretcher and serves as a means for unlocking the stretcher.

When it is desired to shift the stretcher to either side of the truck the cord 38 is pulled. This moves the tumbler 29 back and with it the plunger 28 releasing said plunger from the slot 36. The stretcher is then free to move on the rollers 19 to either side of the truck and any distance within the capacity of the slots 20. The tumbler 30 is pivoted at 30^a upon one side of the plunger, the tumbler 29 is pivoted at 29^a upon the opposite side of the plunger or bolt. When the string 38 is pulled, the tumbler 29 is oscillated upon its pivot against the action of the springs 33, and owing to the fact that both tumblers 29 and 30 pass through the plunger or bolt, the plunger or bolt is withdrawn from the slot or groove 36 of the keeper, then owing to the casing 26 being secured to and carried by the stretcher 22, the stretcher may be moved to one side or the other, in order that the patient may be more readily removed from the stretcher to an operating table and vice versa. When it is desired to return the stretcher to its normal central position, it is accomplished by simply pushing it toward the center, thereby causing one or the other of said noses 31 or 32 (depending on which side of the center the stretcher happens to be) to engage the groove 37. When one or the other of said noses 31 and 32 engage the groove 37, its respective tumbler is oscillated upon its pivot (which pivot is carried by the casing 26), and owing to both tumblers being extended through the plunger or bolt, they are both oscillated laterally against the action of the spring 33, carrying the plunger or bolt with them. In pushing the stretcher toward the center, the bolt or plunger will automatically extend into the slot 36 substantially immediately after either one of said noses 31 and 32 leaves the groove 37, thereby holding the stretcher locked in its central position.

In the hydraulic lift the base 40 is attached by appropriate bolts or screws to the articulate pieces 5. It is counter-bored at 41 to make room for the check valve 42. Integral with 40 is the external oil chamber 43. (This is called an oil chamber because oil is thought to be the most satisfactory liquid for operating the device; oil having both lubricating properties and a low evaporating point. Any other satisfactory liquid may, however, be substituted). Protruding from the oil chamber is the major plunger

44 terminating at its upper end in the support 14 and having at its lower extremity the piston 45 to which the valve 42 is attached by the bolts 46. The bolts 46 do not hold the valve 42 solidly against the piston 45 but permit it to have a slight vertical movement thereon. The major plunger 44 is hollowed out at its center and ports 47 communicate between this interior and the interior of the chamber 43. Internal to and concentric with the plunger 44 is minor plunger 48 with a pilot 49 that projects through an oil tight hole in the valve 42. At its upper end 48 is connected to the operating lever rod 50 by means of the link 51 and eccentric 52. A suitable bearing 53 for the rod 50 is cast integral with the plunger 44 and a further supporting bearing 54 is attached to the under side of the board 15. The rod 50 terminates in the upturned handle 55. With the handle 55 in the position as shown in Fig. 1, the plunger 48 may be said to be at its neutral point. Moving the handle toward the observer will lower plunger 48; moving it away from the observer will raise it. On its downward stroke from the neutral point, the plunger 48 is designed to close the ports 47 during the greater part of the stroke, the pilot 49 the while sliding through and keeping closed the hole in the check valve 42. On its upward stroke from the neutral point, the pilot 49 is withdrawn from the valve 42, thus allowing whatever oil that may be below the piston 45 to flow into the upper part of the chamber 43 as the piston settles down. A round key 56 attached to the chamber 43 at the point where the plunger 44 enters the chamber is adapted to engage the keyway 57 thus preventing the plunger 44 (and with it the stretcher) from turning with respect to the chamber. With the stretcher in the position shown in Fig. 1, the piston 45 is at the bottom of the chamber 43, and the oil (with which said chamber should be filled) is all on top of said piston. With the handle 55 vertical the bottom of the minor plunger 48 is above the ports 47 so that oil is permitted to flow in between the plunger 48 and check valve 42. If the handle 55 is pulled toward the observer, the rod 50 communicates the motion to the eccentric 52 which in turn communicates it to the plunger 48 by means of the link 51. As soon as the end of the plunger 48 has passed the ports 47, the resultant pressure on the oil below the plunger 48 forces the check valve 42 open and transfers the oil below the piston 45, thus raising it with all its attendant parts. The handle 55 is then brought back to a vertical position and the performance repeated with the result that the piston 45 is again raised a small amount. The continued repetition of this operation will result in the ultimate 130

transfer of all the oil below the piston 45 at which time the plunger 44 (and the stretcher connected to it) will be at its highest point. To lower, the handle 55 is moved away from the observer. The eccentric 52 then turning in the opposite direction than previously lifts the plunger 48 and with it the pilot 49 above the neutral point, the pilot 49 leaving its hole in the check valve 42. Egress being thus afforded for the oil below the piston, it continues to flow in on top of said piston as the piston and its parts from their own weight descend. Returning handle 55 to a vertical position terminates this operation by returning the pilot 49 to its hole in the check valve 42.

The invention having been set forth, what is claimed as new and useful is:—

1. In a stretcher, a truck, a lift on said truck, a longitudinal support connected with said lift, a stretcher supported by said longitudinal support, means in the lift for effecting vertical adjustments, means in the support permitting lateral adjustments.

2. In a stretcher, a truck, having a frame composed of two longitudinal pieces, two arched end pieces and two intermediate arcuate ribs, a lift mounted on said ribs, a laterally adjustable stretcher supported by said lift.

3. In a stretcher, a truck, composed of a frame and a transversely disposed wheel supporting member directed upward at each side of the truck and then bent back on its self to form suitable means of con-

nnection to the wheels, wheels connected to said wheel supporting member, swiveled casters at each end of the truck, a lift supported in the middle of the truck, a vertically and laterally adjustable stretcher 40 supported by said lift.

4. In a stretcher, a truck, a lift on said truck, a stretcher carried by said lift, means permitting the stretcher to be moved laterally to either side of the truck, a device for automatically locking the stretcher in the center of the truck.

5. In a stretcher, a truck having channels, means permitting lateral movement of the stretcher, said means comprising depending slotted members operating on rollers mounted in said channels, a locking device for holding the stretcher stationary on its truck.

6. In a stretcher, a truck, a lift on said truck, a supporting member on said lift, channels on each end of the supporting member, rollers in these channels, depending slotted members operating on these rollers, a stretcher secured to the depending members, a locking device for holding the stretcher stationary on its supporting member.

In testimony whereof I have signed my name to this specification in the presence of two subscribing witnesses.

EDWARD TAYLOR.
